Atty.

UNITED STATES PATENT OFFICE.

ELI BELOIN, OF NEW BRITAIN, CONNECTICUT.

GAME.

1,362,218.

Specification of Letters Patent. Patented Dec. 14, 1920.

Application filed April 16, 1920. Serial No. 374,320.

To all whom it may concern:

Be it known that I, ELI BELOIN, a citizen of the United States, residing at New Britain, in the county of Hartford and State of Connecticut, have invented certain new and useful Improvements in Games, of which the following is a specification.

My invention relates to improvements in games of the form that involve the use of a chart in combination with movable men or figures, such as blocks or disks or other movable elements, and adapted to be moved along the chart in some prescribed manner as may be determined by the use of numbers or values obtained by throwing of dice, and the object of my improvement is to produce a chart that is adapted for use in such a game that is relatively simple and easy to understand and that is so constructed and arranged that by means of a few simple rules, involving a combination of special privileges and penalties, there may be aroused interest in the game and rivalry, by reason of the features and conditions existing which permit of the display of judgment and discretion to a considerable extent and also depend to a relatively large extent on the element of chance or luck.

In the accompanying drawing:—

Figure 1 is a plan view of my improved game chart with a complete set of movable elements or men, all set at the position for beginning a game, and a pair of dice for use in determining the movement that is permitted at a particular play.

Fig. 2 is a similar view of the chart with a single man and a single die, adapted for use by a single individual, and illustrating the elementary arrangement and operation of the game.

My improved game involves the use of a chart 10, a set of movable elements or men 11, and a set of dice 12, and these are used in accordance with a set of rules that permit of the exercise of judgment and choice of movement as well as penalties and the like under the different conditions that may arise.

The elementary construction and arrangement of the game may be explained in connection with the elementary form shown in Fig. 2, involving a single man 11 and a single die 12, although even with a single individual a pair of men or a pair of dice may be used.

The chart 10 is preferably made of square

form, although the four corner portions 13 are inactive so far as the actual game is concerned.

The said inactive corner portions 13 are each square and the total chart lay-out is also square, so that the remaining active portion 14 of the chart 10 is in the form of four branch arms 15 that meet at a square 16 at the middle so as to form a cross of the 65 said active portion 14.

The active portion 14 is subdivided by division lines as follows: A pair of main division lines 17 extends entirely across the chart from edge to edge in parallelism and spaced and positioned so as to divide the arms each into three parts that are adapted to be used as travel paths or ways for the men 11 or stations, as will be explained, and also divide the middle junction square 16 75 into a plurality of sub-squares that are adapted to be used as parts of the complete paths or ways and as stations, according to the particular location of each of the said sub-squares.

Other division lines are the cross-lines 18 that extend transversely across the branch arms 14 and by reason of their intersection with the main division lines 17 serve to divide the said branch arms 14 into a plurality 85 of spaces that are adapted to serve as steps and stations in the game.

The sub-division of the middle square 16 by the main lines 17 comprises the square 19 at the middle that is designated as 90 "Home"; a square 20 at the side of the side wall of the said "Home" square 19 on each of the four sides thereof, and designated as the "Home station"; and at each corner there is a corner or junction square 21. 95

The paths along the branch arms 14 comprise a path 22 at the middle, designated as the "Home stretch," and a path on each side thereof comprising the path 23 at the right and the path 24 at the left, and which are 100 marked accordingly at "Right" and "Left."

The sub-division of the paths 22, 23, and 24 by the lines 18 comprises a square at the outer end of each path and a plurality of relatively smaller subdivisions 25 that are 105 intermediate the end squares and the main square 16 at the middle. As shown, there are twelve of the said smaller sub-divisions or spaces 25 and these are adapted to serve as the ordinary steps in the detail of the 110 game.

The said end squares comprise at the mid-

dle, which is the outer end of the "Home stretch," the square 26 that is marked "Start," and a square 27 on each side thereof, being each located at one of the outer 5 corners of the branch arm 14.

The corner squares, comprising the outer corners 27 and the inner, junction corners 21, serve as special stations, and these may be marked in some special manner, as by 10 the diagonal lines 28 shown or by a special color or design.

The four "Start" squares or stations may be numbered consecutively 1, 2, 3, and 4, as shown, going around from left to right 15 corresponding to the direction followed in the playing.

The elementary plan followed in the playing comprises to begin with a man at one of the starting stations 26, move around the 20 peripheral border by moves corresponding in extent to the numbers obtained by throws of the dice until the initial starting station 26 is again reached, and then travel down the "Home stretch" and finally reach 25 "Home", which represents the object to be attained.

Such a peripheral path comprises the following:—From "Start", which may be number 1 or one of the others, the first move is 30 to the right to the adjacent outer corner 28, then along the twelve intermediate right steps 23 to the inner, junction corner 21, when a turn is made to follow the "Left" path in the next branch arm 14, which is 35 continued until the turn is made at the outer corner station 28, and the course is continued until the original starting station 26 is again reached, when the turn is made down the "Home stretch" 22 along the subdivisions 40 29 and into and across the "Home station" 20 into "Home".

While a choice of rules is without limit, as simplicity is generally desirable, a few features that stand merely as suggestions 45 would in most cases be followed, involving a plurality of players.

Thus it is plain that a man on the home stretch would always be safe.

A man overtaking an opponent and coinciding with the particular space or step 50 on which the opposing man is located would have the effect to throw the man back to his start.

The corner stations may be adopted as

safety stations, such as to render the occupant immune from such disturbance, and with a possible penalty for coinciding with the particular location.

In the case of partners, one who has reached the home station may have the 60 choice of entering into the home on his turn to move or may use his dice throw to assist his mate.

Other rules of simple form may be adopted that are readily evolved and kept in 65 mind by reason of the particular layout of the chart.

The preferred plan is to use two dice and two men for each player, the men being distinguished in some convenient manner, as 70 by a difference in shape, as shown, or a difference in color.

I claim as my invention:—

A game chart for use with a set of movable elements and dice comprising an active portion in the form of a cross, composed of a main square at the middle and a set of branch arms extending outwardly from the four sides of the said main square, division lines subdividing the said active 80 portion, comprising a pair of main division lines extending in parallelism from the outer edge of each branch arm, along the length of the arm, across the main square, and meeting and merging with the corresponding main division lines of the opposite arms, and cross division lines extending transversely across each of the branch arms, arranged to subdivide the said active portion so as to provide three paths along the 85 branch arms, with a corner square at the outer end of each of the said paths, and terminal squares at the inner ends of the said paths composed of sub-divisions of the main square, and the said terminal squares being 90 distributed around the periphery of a center square that is also a subdivision of the said main square and adapted to serve as "Home" in use, the terminal square at the side of the center square serving to connect the said 95 "Home" with the middle path of the branch arm opposed thereto, and the terminal square at the corner of the center square in each case serving as a corner and junction square or station intermediate the two side paths of 100 the adjacent branch arms.

ELI BELOIN.
